UNITED STATES PATENT OFFICE.

CHARLES FERGER, OF INDIANAPOLIS, INDIANA.

SNOW-REMOVER.

1,241,102.

Specification of Letters Patent. Patented Sept. 25, 1917.

Application filed June 25, 1917. Serial No. 176,662.

To all whom it may concern:

Be it known that I, CHARLES FERGER, a citizen of the United States, residing at Indianapolis, in the county of Marion and State of Indiana, have invented certain new and useful Improvements in Snow-Removers, of which the following is a specification.

This invention relates to a device for removing snow from side-walks and the like; and the object of the invention consists in the provision of a device of the above character by which side-walks and similar pathways can be readily and economically cleared of snow.

A further object of the invention consists in the provision of a device of the above character which is simple in construction, efficient in operation, and which is cheap to manufacture.

I accomplish the above objects of the invention by means of the construction illustrated in the accompanying drawings, forming a part hereof, in which—

Figure 1 is a top or plan view of my invention. Fig. 2 is a side elevation of the construction shown in Fig. 1. Fig. 3 is a fragmentary detail sectional view, on an enlarged scale, on the line 3—3 in Fig. 1.

Referring to the drawings, 10 represents the draft beam of the device, and one end of beam 10 is provided with a disk-wheel 11 for supporting its forward end and enabling the device to be easily moved. The rear end of the beam 10 is provided with a transverse handle 12. A transverse bar 15 is pivotally secured to the central portion of beam 10 by means of a bolt 17. Attached to bar 15 is a scraper-blade 16 which is curved rearwardly, as shown, to form a scoop for engaging the snow during the advanced travel of the device. Arranged in advance of and parallel with bar 15 is a stationary bar 18 which is rigidly secured to the top of beam 10 by means of the bolts 19. The length of bar 18 coincides substantially with the length of scraper-blade 16, and bar 18 is provided at its ends with cutter or guard-blades 20. Blades 20 cut the snow along parallel lines and separate it from the adjacent mass, thereby enabling the snow to be freely scooped up by scraper-blade 16, when the device is moved forward. Scraper-blade 16

is susceptible of being oscillated about its pivot 17 and may thus be inclined to a plane through the longitudinal axis of beam 10 by means of a shifting-rod 22 which is pivoted at one end to bar 15 at 23, and the other end of rod is adjustably secured to beam 10 by means of a pin 25. The inclination of scraper-blade 16 may be varied by moving rod 22 longitudinally, and said rod is secured in position when one of the apertures 27 is brought into alinement with aperture 28 in beam 10. This adjustability of scraper-blade 16 is desirable where the snow is to be deposited on one side of the pathway to be cleared of snow. As an illustration, if blade 16 is inclined, as indicated by the dotted line in Fig. 1, the snow will be forced out of the end of blade 16 projected toward the top of the sheet, and on the next cut when the device is moving in the opposite direction the inclination of blade 16 is reversed, thereby discharging the snow from the opposite end of the blade 16 but in the same general direction as before. When scraper-blade 16 is inclined one of its ends will be substantially closed against the escape of snow by means of the proximity and contour of adjacent cutter-blade 20, and when the inclination of blade 16 is reversed the opposite end of said blade is closed by the adjacent cutter-blade 20 mounted on the other end of bar 15.

Having thus fully described my said invention, what I desire to secure by Letters Patent is—

A device of the character described comprising a roller-mounted beam, a transverse bar pivotally secured to said beam intermediate its length, a scraper-blade carried by said bar, a rod for changing the angularity of said bar to said beam, a stationary bar arranged in advance of the pivoted bar, means for rigidly securing said stationary bar to said beam, a guard-blade secured to each end of said stationary bar, for closing the adjacent end of the scraper-blade when the latter stands in an inclined position.

In witness whereof I have hereunto set my hand and seal at Indianapolis, Indiana, this 20th day of June A. D. one thousand nine hundred and seventeen.

CHARLES FERGER. [L. S.]
